WAVE RESPONSIVE TRANSMISSION
CONTROLDoren Mitchell, Martinsville, N. J., assignor to
American Telephone and Telegraph Company,
a corporation of New York

Application August 24, 1931, Serial No. 559,079

16 Claims. (Cl. 179—170)

This invention relates to systems for the transmission of energy, such as telephone systems over which are transmitted the electrical waves representing speech. More particularly, the invention relates to telephone circuits—especially four-wire circuits—in which transmission is controlled by switching devices responsive to the energy transmitted thereover for the production of the desired over-all effect, such as the voice waves.

10 In the case of a telephone circuit, it is often desirable to maintain a normal, or non-operating, condition of disability, in order to prevent "singing". It then becomes necessary, of course, to cause the removal of this normal disability 13 when speech energy is transmitted, and it is accordingly important that the removal of the disability be as nearly certain as is possible. Furthermore, in the case of a four-wire circuit, in which the path normally disabled is associated 20 with a path for transmission in the opposite direction (usually through a hybrid coil connection to an extending two-wire circuit), unbalance conditions may, and usually do, result in the reflection of energy transmitted over the latter path 25 into the former, with the possibility of the undesired operation of the wave-responsive apparatus for controlling the transmission paths.

The principal object of the invention is the proper response to the voice waves in a telephone 30 circuit of the apparatus for removing the normal singing suppressing disability.

One of the subordinate objects of the invention is to render the above-discussed wave-responsive apparatus responsive to all voice waves, 35 weak as well as strong, which are to be transmitted over the normally disabled transmission path. Another subordinate object is to keep the sensitivity of this wave-responsive apparatus as low at all times as is consistent with reliable 40 operation. A further object is to control the volume of the energy in the oppositely-directed transmission path of a four-wire circuit with a view to preventing the reflection of waves of sufficient amplitude to cause the above-discussed 45 false operation of the wave-responsive apparatus.

In accomplishing the above-stated objects, the applicant provides for removal of the singing suppressing disability in response to waves in the transmitting path of a predetermined or a 50 greater magnitude, through well-known means such as an amplifier-detector and a relay chain, and provides for an increase of the sensitivity of the wave-responsive means when the transmitted energy is lower than the predetermined magnitude. In addition, in the case of four-wire cir-

cuit operation, provision is made for the introduction of an increased loss in the receiving side of the circuit when the energy in the transmitting side falls below the predetermined level, whereby the chance of the undesired operation 5 of the transmitting switches by echoes is reduced to the minimum.

The invention will be clearly understood when the following description of one desirable embodiment thereof is read with reference to the 10 accompanying drawing.

The single figure of the drawing shows diagrammatically a portion of a two-way system for the transmission of energy such as the waves representing the speech transmitted over a telephone system. There are disclosed two two-wire transmission paths L_1 and L_2 along with the applicant's switching arrangements for transmission control.

The transmission path L_1 is adapted for transmission from left to right while the path L_2 is adapted for transmission from right to left. As is indicated in the drawing, these two paths may be connected at the left end to a two-wire extending circuit. As is well understood in the art, this connection is usually made through a hybrid coil, with the two-wire circuit balanced by a suitable artificial impedance. It will be understood further that the balance between the two-wire line and the balancing impedance is never perfect and 30 that, accordingly, waves passing to the two-wire circuit over the path L_2 may be reflected, in part, over the path L_1 .

It will be noted that the path L_1 is normally disabled at the point a , this disability being under 35 the direct control of the so-called singing suppressor relay SS . Furthermore, provision is made for the disabling of the path L_2 at point c by the operation of a relay S . At the point b , in path L_1 , an amplifier-detector W is bridged across 40 the circuit. It will be noted that the transmission control relays SS and S are associated with the detector output circuit of the amplifier-detector W by circuit arrangements devised by the applicant.

This intermediate apparatus includes relays S_1 , S_2 and S_3 . Relays S_1 and S_2 are polar relays. Relay S_1 has three windings w_1 , w_2 and w_3 . Likewise, relay S_2 has three windings w'_1 , w'_2 and w'_3 . The left-hand windings of these relays, w_1 and w'_1 , are connected in circuit with a battery B_1 through a resistance R_1 , which may be adjustable. These windings serve to hold the armatures of the two relays on their back contacts under normal 50 conditions. Relay S_2 should be slightly more 55

sensitive than relay S_1 , and relay S_3 should be more sensitive than relay S_2 . Associated with this relay chain are a three-electrode vacuum tube T_1 , a condenser C and various resistances and sources of voltage, as will be more fully disclosed hereinafter.

It will be noted further that apparatus is included in the path L_2 furnishing a variable shunt impedance for the circuit. This apparatus includes the three-electrode vacuum tubes T and T' connected substantially as disclosed in the drawing.

The inter-relation and the functions of the various elements of the applicant's circuit will be clearly understood from the following description and discussion of the operation of the system.

When energy is transmitted from left to right over the path L_1 , speech volume is regulated by a suitable device so that constant volume is applied to point b . A portion of the energy is diverted at point b to operate the amplifier-detector W . Connected in the detector output circuit of this device are the winding of relay S_3 , the middle winding w_2' of relay S_2 and the middle winding w_2 of relay S_1 . These middle windings of the relays S_1 and S_2 may be termed the operating windings; it has been noted above that the left-hand windings w_1 and w_1' serve as biasing windings for these relays; the right-hand windings w_3 and w_3' may be termed the auxiliary windings of these relays. It will be remembered that these relays S_1 and S_2 are polar relays; that the various windings are wound to act as is indicated by arrows in the drawing and that the effect of the windings w_1 and w_1' is to hold the armatures on their back contacts. When no current is flowing in windings w_3 and w_3' , relay S_2 is considerably less sensitive than relay S_3 , and relay S_1 is slightly less sensitive than relay S_2 .

If the energy in the path L_1 is of a predetermined or a greater magnitude (which magnitude may be fixed by adjustment of the amplifier-detector W and by adjustment of the resistance R_1), the operation of amplifier-detector W and the resultant current flow in relay S_3 and the middle windings of relays S_2 and S_1 will cause the operation of relays S_1 , S_2 and S_3 . The operation of relay S_2 pulls the armature of that relay to its front contact and completes a circuit through battery B_2 and the windings of relays SS and S . The operation of relay SS removes the normal singing suppressing disability from path L_1 at point a , and the operation of relay S places an echo suppressor disability on path L_2 at the point c . Operation of S_3 closes its contact, but operation of S_1 prevents the charging of condenser C and the increase of sensitivity.

It may be, however, that the subscriber connected to path L_1 has comparatively poor ability to operate relays. In such a case, the operation of amplifier-detector W will cause the operation of relay S_3 but will fail to operate relays S_1 and S_2 . The contact of relay S_3 is now closed while the armature of relay S_1 remains on its back contact. Battery B_3 is now connected through a resistance R_2 , the contact and armature of relay S_1 and the back contact of relay S_1 to the condenser C ; accordingly, while relay S_3 remains operated, this condenser is charged. With the accumulation of the charge on condenser C , two results are accomplished. First, the voltage on the grid of the tube T_1 , which is normally considerably negative by reason of the connection of battery B_4 , is gradually rendered less negative, and current is permitted to flow through the tube

T_1 and the right-hand windings w_3 and w_3' of relays S_1 and S_2 , respectively. Second, the voltage on the grids of the tubes T and T' , which is normally considerably negative by reason of the connection of battery B_5 , is gradually rendered less negative, and the impedance bridged across the path L_2 is gradually decreased.

When the negative voltage on the grid of tube T_1 becomes sufficiently reduced and current flows in the auxiliary windings of the relays S_1 and S_2 , the operation of these two relays is aided, or, in other words, these relays are rendered more sensitive and thus responsive to energy in path L_1 which is below the original or predetermined level. The result is that the relays SS and S are rendered responsive to this lower energy in the transmitting path. It will be noted, however, that the increased sensitivity is not produced unless this is necessary because of low speech energy, and accordingly, the singing suppressor control apparatus remains at a suitably low sensitivity until it is necessary to increase this sensitivity to insure operation of the relay SS .

When the negative voltage on the grids of tubes T and T' is reduced, as described above, in response to the lower energy in path L_1 , the impedance bridged across the receiving path L_2 is reduced, and an increased loss is introduced in this path L_2 . It will be understood that this increase of loss reduces the chance of the undesired operation of the amplifier-detector W and the relays controlled thereby, because of the reflection back over path L_1 of energy coming in over path L_2 , it being borne in mind that the transmission control relays are now more sensitive than normally.

It will be noted that a resistance R_3 is connected in circuit with the condenser C . This resistance should be of such value that the charge on condenser C will leak off quite gradually when the wave-responsive operation ceases.

It has been stated above that relay S_2 is slightly more sensitive than relay S_1 . This arrangement provides a slight margin against clipping, since sensitivity adjustment is made on speech energy which does not quite fail to operate relay S_2 . However, after the sensitivity has been increased sufficiently, relay S_1 will operate on weak speech energy and thus prevent further and unnecessary increase in sensitivity and loss in the receiving path. It may be desirable to employ a delay circuit in path L_1 between points b and a , as shown in the drawing.

It will usually be desirable, in a system such as that described, to provide for the disabling of path L_1 in response to energy transmitted over the path L_2 . For this purpose, a portion of the energy in path L_2 is diverted at point d to operate the amplifier-detector E and the relay S' , which disables the path L_1 at a point e over which energy in path L_1 must pass before operating the amplifier-detector W .

The transmission control arrangements, described above, are such that the sensitivity of the singing suppressing relay SS is automatically raised when this is necessary to insure operation of the relay; but it will be noted that this sensitivity is maintained at the lowest value consistent with certain operation of this relay. It will be noted further that, as the singing suppressor control becomes more sensitive, the loss in the opposite receiving path L_2 is increased, with the result of the above-discussed reduction of false operation of the transmitting relays by reflected energy in the path L_1 . Strong voice waves op-

erate relays S_1 , S_2 and S_3 , and there is normal operation of relays S_2 and S_3 , without increase of sensitivity or increase of loss in the path L_2 . Voice waves which are weaker, but above the noise level, operate relay S_3 and cause an increase of sensitivity in S_2 sufficient to permit its prompt operation; at the same time the loss in line L_2 is increased for the purpose of avoiding operation of the relays by echoes reflected over line L_1 . Relay S_3 must operate on any wave of amplitude above the noise level. Relay S_2 must not be operated by echoes of transmission which is too weak to operate relay S_3 .

While the invention has been disclosed in a specific embodiment for the purpose of illustration, it will be understood that it is capable of embodiment in many other and widely different forms within the scope of the appended claims.

What is claimed is:

1. In a system for the transmission of energy, a transmission path, means for normally disabling said path, control means adapted to remove the normal disability from said path, means normally responsive to energy of a predetermined or greater magnitude in said path for operating said control means, and auxiliary means responsive to energy in said path of less than the predetermined magnitude for rendering said operating means responsive to such energy.

2. In a system for the transmission of energy, two paths adapted for transmission in opposite directions, the first path being subject to the reflection thereover of energy normally transmitted over the second path, means for normally disabling the first path, means in the second path for introducing a variable loss therein, control means adapted to remove the normal disability from said first path, means normally responsive to energy of a predetermined or greater magnitude in said first path for operating said control means, auxiliary means responsive to energy in said first path of less than the predetermined magnitude for rendering said operating means responsive to such energy, and means responsive to energy in said first path of less than the predetermined magnitude for increasing the loss introduced in said second path by said variable loss introducing means.

3. In a system for the transmission of energy, two paths adapted for transmission in opposite directions, means for normally disabling the first path, control means adapted to remove the normal disability from said first path and to disable the second path, means normally responsive to energy of a predetermined or greater magnitude in said first path for operating said control means, and auxiliary means responsive to energy in said first path of less than the predetermined magnitude for rendering said operating means responsive to such energy.

4. In a system for the transmission of energy, two paths adapted for transmission in opposite directions, the first path being subject to the reflection thereover of energy normally transmitted over the second path, means for normally placing a disability on the first path, means in the second path for introducing a variable loss therein, control means adapted to remove said disability from said first path and to disable said second path, means normally responsive to energy of a predetermined or greater magnitude traveling in said first path toward the point thereon of normal disability for operating said control means, auxiliary means responsive to energy in said first path of less than the predetermined magnitude

for rendering said operating means responsive to such energy, means responsive to energy in said first path of less than the predetermined magnitude for increasing the loss introduced in said second path by said variable loss introducing means, and means responsive to energy in said second path for disabling said first path at a point over which energy therein must pass before affecting said operating means.

5. In a system for the transmission of energy, two paths adapted for transmission in opposite directions, the first path being subject to the reflection thereover of energy normally transmitted over the second path, means for normally disabling the first path, means in the second path for introducing a variable loss therein, control means adapted to remove the normal disability from said first path, means normally responsive to energy of a predetermined or greater magnitude in said first path for operating said control means, auxiliary means responsive to energy in said first path of magnitude less than sufficient to cause the operation of said operating means for increasing the sensitivity of said operating means, means responsive to energy in said first path of such lesser magnitude for increasing the loss introduced in said second path by said variable loss introducing means, and means for preventing said increase of sensitivity and said increase of loss while such increases are unnecessary to the operation of said disability removing means.

6. In a system for the transmission of speech energy, including two paths adapted for transmission in opposite directions, the first path being subject to the reflection thereover of energy normally transmitted over the second path, and means in the second path for introducing a variable loss therein, the method of transmission control which consists in causing the first path to be normally disabled, causing energy in said first path of a predetermined or a greater magnitude within certain predetermined limits but substantially about the lower of said limits to remove the normal disability therefrom, and causing energy in said first path within said limits but of less than the predetermined magnitude to remove the normal disability from said first path and to increase the loss introduced in the second path by said variable loss introducing means.

7. In a system for the transmission of energy, including two paths adapted for transmission in opposite directions, the first path being subject to the reflection thereover of energy normally transmitted over the second path, means for normally disabling the first path and means for introducing a variable loss in the second path, the method of transmission control which consists in causing energy in the first path of a predetermined or a greater magnitude within certain predetermined limits but substantially above the lower of said limits to remove the normal disability therefrom and causing energy in said first path within said limits but of less than the predetermined magnitude to remove said disability and to adjust the loss introduced by said means in said second path.

8. In a system for the transmission of energy, including two paths adapted for transmission in opposite directions, the first path being subject to the reflection thereover of energy normally transmitted over the second path, means for normally disabling the first path, control means adapted to remove the normal disability from said first path, means normally responsive to energy of a predetermined or greater magnitude in said first

- path for operating said control means and gain control means for introducing a variable loss in the second path, the method of transmission control which consists in causing energy in said first path of less than the predetermined magnitude to render said operating means responsive to such energy, and causing energy in said first path of less than the predetermined magnitude to change the loss introduced in said second path by said 10 gain control means.
9. In a circuit for the transmission of energy, the method of transmission control which consists in rendering the circuit disabled under conditions of non-operation, causing energy of rapidly fluctuating level such as speech, as distinguished from noise, in the circuit of a predetermined or a greater magnitude within certain predetermined limits but substantially above the lower of said limits to produce a normal operation, removing the non-operative disability, and causing such energy in the circuit within said limits but of less than the predetermined magnitude to produce an operation auxiliary to said normal operation for removing said disability in 20 response to the transmission of such lower energy.
10. In a system for the transmission of alternating currents, a transmission path, means for normally disabling said path, means in said path ahead of said disabling means for regulating the volume in said path to bring the amplitudes within certain limits, control means normally responsive to energy in said path, at a point intermediate said regulating means and said disabling 30 means, of a predetermined or greater magnitude within said limits but substantially above the lower of said limits for removing the normal disability from said path, and means responsive to energy in said path, at said intermediate point, within said limits but of less than said predetermined magnitude for rendering said control means responsive to such energy, means responsive to energy in said first path at said intermediate point, within said limits but of less than said predetermined magnitude for increasing the loss introduced in said second path, and means responsive to energy in said second path for disabling said first path at a point over which energy therein must pass before affecting said control means.
11. In a system for the transmission of alternating currents, two paths adapted for transmission in opposite directions, the first path being subject to the reflection thereover of energy normally transmitted over the second path, means for normally disabling the first path, means in the second path for introducing a variable loss therein, means in said first path ahead of said disabling means for regulating the volume in said path to bring the amplitudes within certain limits, control means normally responsive to energy in said first path, at a point intermediate said regulating means and said disabling means, of a predetermined or greater magnitude within said limits but substantially above the lower of said limits for removing the normal disability from said first path, means responsive to energy in said first path within said 50 limits but of less than said predetermined magnitude for rendering said control means responsive to such energy, and means responsive to energy in said first path within said limits but less than said predetermined magnitude for increasing the loss introduced in said second path.
12. In a system for the transmission of alternating currents, two paths adapted for transmission in opposite directions, means for normally disabling the first path, means in said first path ahead of said disabling means for regulating the volume in said path to bring the amplitudes within certain limits, control means normally responsive to energy in said first path, at a point 70 intermediate said regulating means and said disabling means, of a predetermined or greater magnitude within said limits but substantially above the lower of said limits for removing the normal disability from said first path, and means responsive to energy in said first path within said limits but of less than said predetermined magnitude for rendering said control means responsive to such energy.
13. In a system for the transmission of alternating currents, two paths adapted for transmission in opposite directions, the first path being subject to the reflection thereover of energy normally transmitted over the second path, means for normally placing a disability on the first path, means in the second path for introducing a variable loss therein, means in the first path ahead of said disabling means for regulating the volume in said path to bring the amplitudes within certain limits, control means normally responsive to energy in said first path, at a point intermediate said regulating means and said disabling means, of a predetermined or greater magnitude within said limits but substantially above the lower of said limits for removing said disability from said first path and for disabling the second path, and means responsive to energy in said first path, at said intermediate point, within said limits but of less than said predetermined magnitude for rendering said control means responsive to such energy.
14. In a system for the transmission of alternating currents, two paths adapted for transmission in opposite directions, the first path being subject to the reflection thereover of energy normally transmitted over the second path, means for normally disabling the first path, means in the second path for introducing a variable loss therein, means in said first path ahead of said disabling means for regulating the volume in said path to bring the amplitudes within certain limits, control means normally responsive to energy in said first path, at a point intermediate said regulating means and said disabling means, of a predetermined or greater magnitude within said limits but substantially above the lower of said limits for removing the normal disability from said first path, auxiliary means responsive to energy in said first path, at said intermediate point, within said limits but of less than said predetermined magnitude for increasing the sensitivity of said control means, means responsive to energy in said first path, at said intermediate point, of such lesser magnitude for increasing the loss in said second path, and means for preventing said increase of sensitivity and said increase of loss while such increases are unnecessary to the operation of said disability removing means.
15. In a system for the transmission of alternating currents, including two paths adapted for transmission in opposite directions, the method of transmission control which consists in causing the first path to be normally disabled at a first certain point, regulating the volume in said first path at a second certain point ahead of said first point to bring the amplitudes within certain 75

limits, causing energy in said first path at a point intermediate said first and second points which energy is of a predetermined or greater magnitude within said limits but substantially above the lower of said limits to remove the normal disability from said first path, and causing energy in said path at said intermediate point which energy is within said limits but of less than said predetermined magnitude to remove the normal disability from said first path and to increase the loss in said second path.

16. In a system for the transmission of alternating currents, including two paths adapted for transmission in opposite directions, the first path being subject to the reflection thereover of energy normally transmitted over the second path, means for normally disabling the first path at a first certain point and means for introducing a

variable loss in the second path, the method of transmission control which consists in regulating the volume in said first path at a second certain point ahead of said first point to bring the amplitudes within certain limits, causing energy in said first path at a point intermediate said first and second points which energy is of a predetermined or greater magnitude within said limits but substantially above the lower of said limits to remove the normal disability from said first path, and causing energy in said first path at said intermediate point which energy is within said limits but of less than said predetermined magnitude to remove said disability and to adjust the loss introduced by said means in said second path.
